UNITED STATES PATENT OFFICE

2,271,488

BUILDING BOARD BUNDLE

John H. Nold, Hinsdale, Ill., assignor to United States Gypsum Company, Chicago, Ill., a corporation of Illinois

Application November 21, 1938, Serial No. 241,534

2. Claims. (Cl. 206—60)

This invention relates to bundling devices for building boards and has reference more particularly to bundles of plaster boards of the perforated type.

In the manufacture and sale of gypsum plaster boards, it has been customary to arrange the boards in bundles with edge strips of paper holding the boards together in bundle form. Such a bundle is described in patent to Birdsey No. 1,696,877. There has also come into use plaster boards with spaced perforations which register in a bundle, these perforations being for the purpose of forming a firm key with a layer of plaster applied to plaster boards forming a partition. I have found that the perforated plaster boards may be firmly bundled at less expense by attaching means extending through the registering perforations of the bundle.

An object of this invention therefore, is to provide bundling means for use with perforated plaster boards.

Another object of the invention is to provide bundling means which will firmly unite plaster boards in a bundle without necessitating the use of edge bundling strips.

A further object of the invention is to provide a bundling device which will be inexpensive to apply and easy to remove; also to improve bundles and bundling devices in other respects herein-after specified and claimed.

Reference is to be had to the accompanying drawing forming a part of this specification, in which

Fig. 1 is a perspective view of my improved bundle,

Fig. 2 is a sectional elevation through the improved bundle taken on line 2—2 of Fig. 1,

Fig. 3 is a sectional elevation through the bundling device,

Fig. 4 is an end view of a modified form of bundling device,

Fig. 5 is a side elevation of the bundling device shown in Fig. 4,

Fig. 6 is a longitudinal sectional view through a further modified form of bundling device,

Fig. 7 is an end view of the bundling device shown in Fig. 6,

Fig. 8 is an elevation partly in section of a tool for disengaging the bundling devices shown in Figs. 1—5, and

Fig. 9 is a transverse section view through the tool taken on line 9—9 of Fig. 8.

In the manufacture of plaster boards, such as those having a gypsum core and paper cover sheets, it is desirable to ship out the boards in

bundle form. Such a bundle is illustrated in Fig. 1, in which six boards 10 are arranged in face to face relation with the edges of the boards in alignment. It is quite common to provide said boards 10 with spaced holes or perforations 11 so that plaster applied to the face of the boards in a wall will more perfectly bond with the boards and improve the fire resistance of the wall. These holes 11 may be formed by drilling after 10 the bundle is formed or they may be formed by punching the boards, either in the damp or dry states. The holes 10 in the bundle of boards are usually in approximate registry one with the other. The salient feature of my invention constitutes binding means passing through a plurality of holes in the boards of a bundle, in order to bind the bundle of boards together for shipment.

In the form of the invention shown in Figs. 20 1, 2 and 3, I provide a large diameter tube 12 which has an outside diameter somewhat less than that of the holes 11. An outstanding annular flange 13 is formed at one end of tube 12 and an inwardly extending annular flange 14 is 25 formed at the other end of said tube 12. A tube 15 has an outside diameter somewhat less than the inside diameter of flange 14 into which it telescopes. An outstanding annular flange 16 is formed around one end of the tube 15 so that 30 when the tubes 12 and 15 are in telescoped arrangement in one of the holes 11, the bundle of boards will be confined between tube flanges 13 and 16. In order to lock the tubes 12 and 15 in telescoped relation, I provide a series of struck 35 out lugs 18 arranged in a spiral series around tube 15. One of said lugs 18 engages the flange 14, the particular lug in engagement depending on how far the bundle permits the tubes 12 and 15 to telescope. The lugs 18 have a certain 40 amount of springiness so that when a lug is depressed to pass the flange 14, it again springs outwardly to lock behind the flange 14. One of these bundle binding devices may be used adjacent each end of the bundle, as shown in Fig. 1, 45 so as to firmly unite the boards 10 in bundle form. In order to separate the boards after delivery, I provide the workman with a cutting tool comprising a handle 19, a stem 20 and a disc 21 on the end of the stem 20, said disc having an outside 50 diameter somewhat less than the inside diameter of tube 15. A cutting point 22 is formed on the edge of disc 21. To disengage the bundle, the disc 21 is thrust into the tube 15, the cutting point 22 forming a longitudinal cut 23 in the wall 55 of the tube. The handle 19 is then manually

rotated and the cutting point 22 cuts off the tube 15 and the bundle of boards can then be separated and formed into a wall or partition. A washer 24 secured to stem 20 limits the inward movement of disc 21.

In the form of the device shown in Figs. 4 and 5, I provide a tube 26 which has a preformed annular flange 27 formed around one end. After a pair of tubes 26 are inserted through bundle holes 11, a riveting head 28 forms flanges 29 around the top end of the tube 26 to lock the boards 10 in bundle form. A cutting tool as previously described may be used to separate the bundle at the job. If desired, both flanges 27 and 28 may be formed simultaneously by opposed riveting heads 28. The tubes 12, 15 and 26 may be made of thin metal, but any other suitable material may be used.

The form of bundling device shown in Figs. 6 and 7 is especially useful where the holes 11 in the bundle of boards are not in exact alignment, as when the holes are punched prior to bundling before the boards have been dried. In this form of bundling device, I force a strip of metal 31 through holes 11 of a bundle, said strip 31 being somewhat wider than the diameter of holes 11 so that the strip 31 will force itself through the holes in a bundle whether or not said holes are in exact registry. A transversely extending preformed flange 32 is formed at one end of the strip 31 and after assembly of the bundling device, the end of the strip 31 is bent transversely to form flange 33, so that the bundle of boards is confined between flanges 32 and 33. One of the flanges 32 or 33 is bent outwardly with a flat tool at the job to release the bundle of boards 10.

In all forms of the bundling devices, consider-

able pressure is applied to the bundle at the time of assembly, so that retaining flanges 13, 16, 27, 29, 32 and 33 bite into the exposed surfaces of the boards so as to lie generally below said surface. This is an advantage in that when the bundles are stacked in a pile, the flanges of the bundling devices will not scratch or mar the cover sheets of adjoining bundles.

I would state in conclusion that, while the illustrated examples constitute practical embodiments of my invention, I do not wish to limit myself precisely to these details, since manifestly the same may be considerably varied without departing from the spirit of the invention as defined in the appended claims.

Having thus described my invention, I claim as new and desire to secure by Letters Patent:

1. In a bundling device, the combination with a plurality of gypsum composition building boards 20 in face to face abutting relation, said boards having a series of substantially registering holes, of a pair of telescoping tubular members having outstanding flanges at the ends thereof for confining said boards in bundle form, and interlocking means between said tubular members for adjustably connecting said tubular members.

2. In a bundling device, the combination with a plurality of building boards in face to face abutting relation, said boards having a series of substantially registering holes, of a pair of telescoping tubular members having outstanding flanges at the ends thereof for confining said boards in bundle form, outstanding spring lugs struck from one of said tubular members for adjustably engaging with the other of said tubular members so as to connect said members together in bundle confining relation.

JOHN H. NOLD.
